Des. 228,143
Patented Aug. 14, 1973

228,143

TOY AMUSEMENT PARK

Norman Spiegel, New York, N.Y., assignor to
NASTA Industries, Inc.

Filed Jan. 12, 1972, Ser. No. 218,665

Term of patent 14 years

Int. Cl. D21—01

U.S. Cl. D34—15 Q

FIG. 1

FIG. 2

FIG. 3

FIG. 4

FIG. 5

FIG. 1 is a top plan view of a toy amusement park showing my new design;

FIG. 2 is a front elevational view thereof;

FIG. 3 is a right side elevational view thereof;

FIG. 4 is a rear elevational view thereof; and

FIG. 5 is a left side elevational view thereof.

I claim:

The ornamental design for a toy amusement park, as shown.
